C. B. FERRO

TRAFFIC SIGNAL FOR MOTOR VEHICLES

Filed Nov. 6, 1924

UNITED STATES PATENT OFFICE.

CLAUDE B. FERRO, OF SAN BERNARDINO, CALIFORNIA.

TRAFFIC SIGNAL FOR MOTOR VEHICLES.

Application filed November 6, 1924. Serial No. 748,108.

My invention is a traffic signal of the semaphore type for motor vehicles. The semaphore arm is pivotally attached to a fixed part of the vehicle, preferably the 5 windshield, and has a handle extending into the vehicle to a convenient position to be grasped by the driver. By swinging the handle downwardly the semaphore may be positioned at an angle of substantially 45° 10 upward to give a right turn signal, or extended horizontally to give a left turn signal, and also shifted to point downwardly 15 at about 45° giving a stop signal.

In the specific construction I secure a 15 fixed disc by a bolt through the center to a part of the vehicle with the face of the disc in a vertical position and transverse to the line of movement of the vehicle. An insulated plate faces on the disc. A second 20 metal disc is rotatably mounted on the bolt and has the handle on the inside of the vehicle and the semaphore arm with a lamp and colored glass indicator on the outside. Electrical make and break springs form a 25 contact between the fixed metal plate and the rotating plate. An outside disc has springs which press the two metal plates toward each other. Thus when the handle is swung into the three positions above mentioned, an electrical contact is made at each 30 position and causes the light to glow.

My invention will be more clearly understood from the accompanying specification and drawings, in which:

Figure 1 is a rear view of the semaphore signal partly in section.

Fig. 2 is a horizontal cross section on the line 2—2 of Fig. 1 showing diagrammatically the electric circuit.

Fig. 3 is a detail showing the spring supporting plate and springs to press the conducting plates together.

Fig. 4 is a section showing a spring pressed ball and socket to hold the semaphore in its several positions.

Fig. 5 is a diagrammatic view illustrating the semaphore in its various positions.

Figure 6 is a detail section through the make and break electrical contacts on the 50 fixed and oscillating discs.

In the drawings the windshield frame is indicated by 1, holding the windshield 2. A clamp 3 having an arm 4 engages over the windshield frame. An aperture 5 through 55 the clamp is provided for a stationary bolt 6 which may be rounded at the portion ex-

tending through the clamp as indicated at 7, and squared at the other end indicated at 8. A stationary metal disc 9 having an aperture 10 therethrough is supported on the 60 bolt 6 and abuts against the clamp 3.

Three springs 11 are secured to the disc by a rivet or welding as indicated at 12. A stationary insulating disc 13 abuts against the disc 9 and preferably has a squared 65 aperture 14 to engage the squared end 8 of the bolt 6 and has an elongated curved slot 15 in which are located the springs 11. A ball 13' is actuated by a spring 14' in a recess 15' in the disc 13. A handle disc 16 is 70 rotatably mounted on an insulated bushing 17, which latter is fixedly carried by the bolt 6 and has three slight recesses 16' to engage the ball 13'. Rigidly attached to one side of the disc is the handle 18 which preferably 75 has a recess 19 which may be loaded with lead or other weight to adjust the counterbalancing of the semaphore arm and the parts attached thereto. The semaphore arm 20 is preferably welded or otherwise secured 80 to the disc 16 and carries at its outer end a lamp socket 21 with a lamp 22 secured therein. An electric lead 23 connects from the socket through a battery 24 illustrated diagrammatically in Fig. 2, and a lead 25 to a ground 26 indicated as part of the windshield. The other terminal of the lamp is preferably grounded to the semaphore arm 20. The semaphore arm carries at its outer 85 end and surrounding the lamp a frame 27 90 which is shown of triangular shape and having glass panels 28, preferably of red glass.

A plate 29 secured to the base 30 of the frame allows the replacement of electric bulbs. A stud 31 is welded or otherwise 95 secured to the disc 16 in order to make contact with the springs 11.

A plain disc 32 of insulating material abuts against the face of the disc 16 and preferably has a squared aperture to engage 100 the squared end 8 of the bolt 6.

An outside disc 33 preferably formed of metal has a squared aperture to engage the squared end 8 of the bolt 6. Secured to this plate are springs 34 fastened by rivets 105 35 or welded. These springs contact with and bear against the insulated disc 32. The inner end of the bolt 6 is preferably screw threaded at 36 and has a nut 37 engaging the face of the disc 33 and a lock nut 38. 110 The fixed disc 9 is held by the clamp 3 and the outside disc 33 is held by the nuts 37 and

38, hence when the springs 34 bear against the insulating disc 32 the pressure is transmitted to the oscillating disc 16 which in turn transmits pressure to the insulating disc 13 and hence to the fixed disc 9, thus all these parts are contained in compact relation and accurately positioned so that the make and break contacts between the springs 11 and the studs will always function when the springs and the studs are in contacting relation to each other.

15 A covering 39 formed of leather, rubber or metal is secured over the edges of the discs to prevent rain or snow from working in between the discs.

The mode of operation of the signal is as follows:

20 On account of the manner of the clamping of the discs together as above mentioned, the springs 34 on the disc 33, the insulating disc 32, the metal disc 16, the insulating disc 13, and the metal disc 9 are pressed tightly together. When the disc 16 is oscillated by grasping the handle 18, the semaphore arm 20 is swung to different positions. As the disc 9 and the springs secured thereto are stationary, the stud 31 may be brought into contact with any one of the three springs 11 moving in the elongated slot 15. This action makes and breaks the electric circuit from the battery 24 through the lead 23 to one side of the lamp. From the other side of the lamp the circuit is continued, grounded to the arm 20 through the disc 16, stud 31, spring 11, disc 9, bolt 6, clamp 3 to the ground at the windshield, and thence from the ground terminal 26 through the lead 25 to the battery 24. The spring pressed ball 13' engaging in any one of the three recesses 16' in the disc 16 holds the semaphore arm in its adjusted position. In this manner the semaphore arm can be held in a position pointing upward at approximately 45° giving the usual right turn signal, pointing directly horizontal giving the usual left turn signal, or pointing downwardly at an angle of 45° giving the usual stop signal. At each of these signaling positions the lamp will become illuminated. 45 It is preferable to have all the discs pressed sufficiently tight together so that the semaphore will remain stationary in any position independent of the spring pressed ball 13'.

50 From the above description, together with the drawings, it will be seen that I have developed a compact form of signal having a fixed disc insulated from an oscillatable disc, these two discs being of conducting material. An outside disc has springs thereon which bear against insulating material, hence as the fixed and outside discs are maintained at a constant distance apart, the fixed and oscillating discs are pressed towards each other. These discs have electrical contacts which 55 in the proper position engage and make an

electric circuit and in other positions disengage and break the circuit.

While I have described the semaphore as being attached to the windshield of a vehicle, it may be secured to any desired part 70 of the vehicle, provided the disc 9 is grounded.

The springs 11 may be constructed secured by the rivet at one end, bowed upwardly in the center and with the free end bent into 75 contact with the disc 9 to which the rivet 12 is secured so that the stud 31 will readily ride over the said springs.

Various changes may be made without departing from the spirit of the invention as 80 claimed.

I claim:

1. A traffic signal comprising in combination a fixed conducting disc, an oscillating conducting disc, means to secure the fixed disc to a vehicle and pivotally mount the oscillating disc in relation to the fixed disc, a stationary insulating disc between the fixed and oscillating discs and having a slot 90 therein, a handle and semaphore connected to the oscillating disc, a lamp to illuminate the semaphore, an electrical circuit to and from the lamp, electrical make and break contacts on the fixed and oscillating disc located in the slot in the insulating disc and 95 actuated to make and break the electric circuit by movement of the handle.

2. A traffic signal comprising in combination a pivot pin, means to secure same to a vehicle, a fixed conducting disc mounted 100 thereon, a stationary insulating disc abutting against the fixed disc, an oscillating conducting disc having attached thereto a handle and a semaphore, an outside stationary disc having springs thereon, said springs 105 pressing the fixed stationary and oscillating discs together, and electric contacts on the fixed and oscillating discs.

3. A traffic signal as claimed in claim 2 having a lamp to illuminate the semaphore, an electric circuit to and from the lamp, and the electrical make and break contacts on the fixed and oscillating discs having relative movement in a slot in the fixed insulating disc.

4. A traffic signal comprising in combination a pivot pin, means to secure same to a vehicle, a fixed conducting disc connected to the pin, a stationary insulating disc abutting the fixed disc, an oscillating conducting disc having a handle and semaphore, a circuit make and break means between the fixed and oscillating discs, an insulated bushing on the pin upon which the oscillating disc operates, a second insulating disc abutting the oscillating disc, an outside disc mounted on the pin, and means to press the fixed disc, oscillating and both the insulating discs together.

5. A traffic signal as claimed in claim 4 130

having in addition an electric lamp to illuminate the semaphore, an electric circuit therefor, and the means to make and break the circuit comprising spring and stud contacts on the fixed and oscillating discs operating in a slot in the first mentioned insulating disc.

6. A traffic signal comprising in combination a pivot pin, means to secure same to a vehicle, a fixed electrically conducting disc on the pin, having electric contact springs on an arc thereon, a stationary insulating disc abutting the fixed disc and having an arcuate slot, an oscillating metallic disc having a handle and a semaphore with a stud on the metallic disc to engage the said contact springs through the slot, an insulated

bushing on the pin upon which the oscillating disc operates, a second insulating disc abutting the oscillating metallic disc, an outside disc mounted on the pin, spring means to press the fixed disc, the oscillating and both the insulating discs together, an electric lamp mounted in the semaphore, a battery, a lead from the battery to the electric light, a second lead from the battery to a ground and thence to the pin and from the pin through the stationary conducting disc, the spring contacts and the stud to the oscillating disc and a ground from the lamp to the oscillating disc.

In testimony whereof I have signed my name to this specification.

CLAUDE B. FERRO.
